UNITED STATES PATENT OFFICE.

LETTERIO FIORE, OF NEW YORK, N. Y.

COMBINATION-GARMENT.

1,311,600.

Specification of Letters Patent. Patented July 29, 1919.

Application filed April 6, 1917. Serial No. 180,281.

To all whom it may concern:

Be it known that I, LETTERIO FIORE, a subject of the King of Italy, residing at New York, in the county of New York and State of New York, have invented certain new and useful Improvements in Combination-Garments; and I do hereby declare the following to be a full, clear, and exact description of the invention, such as will enable others skilled in the art to which it appertains to make and use the same.

My invention relates to an improved child's garment, and has for an object the production of a combined dress and rompers possessing benefits of economic usefulness, style and convenient adaptability, whereby the garment can be easily and comfortably fitted, readily removed and advantageously handled when being washed, pressed and the like.

Another object of my invention is to produce a combined garment consisting of an outer dress portion capable of embodying the season's style or design, and an under-garment in the form of rompers or drawers, both of said garments being open throughout their length and capable of being folded out into a substantially flat position for pressing and other purposes.

Another object of my invention is the production of a combined garment including an outer dress, and an inner garment spaced from the outer dress beginning at a point approximating the waist line, the said inner garment being cut to form rompers or drawers when fastened at the crotch thereof.

With these and other objects in view the invention further consists in producing a child's garment, the waist, skirt and rompers being cut so as to be subsequently joined together in a convenient manner at a point approximating the waist line for relatively strengthening the garment against possible tearing or ripping usually resulting from extensive play or exercise.

In the drawings which show two embodiments of my garment,

Figure 1 is a perspective view of a combined dress and rompers showing the dress portion open throughout its length and the rompers buttoned to form the leg portion of the garment.

Fig. 2 is a vertical sectional view through the combined garment.

Fig. 2^a is an enlarged detail sectional view

of the binding for joining the waist, the rompers and skirt.

Fig. 3 is a detailed perspective view of the lower portion of the garment with the dress and rompers in opened position, and showing their relative positions in dotted lines when spread out for pressing.

Fig. 4 is a perspective view of a modified form of the garment not open throughout its length.

Fig. 5 is a vertical sectional view through the garment shown in Fig. 4, and

Fig. 6 is a detailed perspective view of the lower portion of the garment showing the rompers in opened position.

The present invention has been designed to combine the relative advantages obtained from the use of the ordinary so-called rompers and the additional esthetic appearance of the varying styles of dress which in the present instance will conceal the rompers from casual view and at the same time give ample freedom for all forms of play.

The garment comprises the dress 1, which may be of any suitable style, including the collar 2, belt 3, skirt portion 4, and the rompers or drawers 5 secured to the dress at a point approximating the waist line. The dress as shown in the preferred form of my invention is opened throughout its length as at 6, and suitable fastening devices 7, such as buttons and the like, may be employed to hold the garment in place. As shown, I prefer to use the concealed form of buttons, which when the dress is fastened serves to give it the appearance of a one-piece suit with plaited skirt. The dress is preferably cut with a waist portion 8 to which is secured the skirt 4. The waist portion and skirt are joined to the rompers at or about the waist line in a manner now to be described.

As shown in Fig. 2 of the drawings, the waist 8 is folded back upon itself as at 9 overlapping the upper edge 10 of the skirt 4 against which latter is laid the upper edge 11 of the rompers 5. A suitable binding 12 is stitched over these lapped edges, as shown. The joining of the several portions of the garment at this point forms substantially a waist band which will lay snugly against the inner portion of the garment. From this construction it will be seen that the strength of the garment is materially increased because of the overlapping of the aforesaid

edges in a plane coincident to the strain to which the garment may be subjected.

The rompers 5 comprise relative leg portions 13 and 14 and an intermediate crotch flap 15 of sufficient width to space and form the openings in the leg portions, as shown. Suitable fastening devices 16 are carried by the rompers to which the flap 15 is detachably secured. The rompers are open throughout their length as at 17 and are further provided with fastening devices 18 for fastening the rompers when in position upon a child. The rompers are preferably cut to snugly fit the lower portion of the body and serve as a ready substitute for other undergarments, such as paddies now generally used. The skirt may have a sufficient fullness to permit freedom of play and at the same time preserve the usual appearance of a stylishly designed garment.

In use, the garment may be opened throughout its length and readily fitted to the body in the manner of a coat. The rompers portion may be easily fastened as shown in Fig. 1, after which the dress can be secured. It will be readily understood that the reverse of this order may be employed, that is to say, the rompers may be fastened and unfastened wholly independent of the dress portion as occasions require. When it is desired to remove the garment, it will be seen that its construction permits of its being spread out in substantially a flat form, thereby facilitating the pressing of any portion thereof in a convenient manner. It will be apparent that the dress portion can be readily pressed, likewise the rompers, and in either event there is no separate detachment of either.

Referring to Figs. 4, 5, and 6, a modified form of the combined garment is shown wherein instead of opening the dress throughout its length it may be desirable to employ a style designed to slip over the head. The form of rompers employed may be also of that same general type. In this form shown the dress 19 is formed with a

waist portion 20 and a skirt 21, the lapped edges of which abut against each other and the edge of the rompers 22, there being a binding strip 23 stitched around the abutting edges to form the waist band for strengthening the garment, as shown in Fig. 5 of the drawings. The rompers 22 are provided with leg portions 24 and 25 between which the crotch flap 26 is designed to be fastened. Suitable fastenings 27 hold the crotch flap 26 in position when fitted to the body. It will be seen that this form of the combined garment may be also readily pressed. From the foregoing it will be seen that I have produced a combined child's garment possessing advantages of utility when viewed from the various cares incident to childhood, and the additional aesthetic benefits which go to make up the style of the garment.

Having thus described my invention, what I claim and desire to secure by Letters Patent is:

70

1. A garment comprising a waist and skirt open throughout its length, a leg covering secured to said garment at a point approximating the waistline, said leg covering having an opening extending from the upper to the lower edges thereof, and means for detachably closing the leg covering whereby leg openings are formed therein.

2. A garment comprising a waist and skirt open throughout its length, a leg covering secured to said garment at a point approximating the waistline, said leg covering having an opening coincident with the aforesaid opening in the waist, and skirt, and extending from the upper to the lower edges thereof, and means for detachably closing the leg covering whereby leg openings are formed therein.

80

In testimony whereof I affix my signature, in presence of two subscribing witnesses.

LETTERIO FIORE.
